TELEPHONE TABLE

James F. Antonio, 826 S. Osage St., and Floyd L. Antonio, 2250 W. Kentucky Ave., both of Denver, Colo.

Filed Sept. 10, 1959, Ser. No. 57,500

Term of patent 14 years

(Cl. D33—14)

Fig. 1 is a perspective view of the left side and front of a telephone table showing my new design;

Fig. 2 is an elevational view of the right side thereof; and

Fig. 3 is a perspective view of the right side and back thereof.

We claim:

The ornamental design for a telephone table, as shown.
